US00D591754S

(12) **United States Design Patent**
Hwangbo et al.

(10) **Patent No.:** **US D591,754 S**
(45) **Date of Patent:** **** May 5, 2009**

(54) **MEMORY CARD**

(75) Inventors: **Hyung-Ho Hwangbo**, Seoul (KR);
Tae-Ho Kim, Yongin-si (KR); **Ri-Na Sin**, Seoul (KR)

(73) Assignee: **Samsung Electronics Co., Ltd.**,
Suwon-Si (KR)

(**) Term: **14 Years**

(21) Appl. No.: **29/321,315**

(22) Filed: **Jul. 15, 2008**

(51) **LOC (9) Cl.** **14-02**

(52) **U.S. Cl.** **D14/436**
